DECORATIVE ORNAMENT

Jay T. Stauffer, Lititz, Pa., assignor to Wilton
Brass Company, Columbia, Pa.

Filed June 18, 1971, Ser. No. 154,483

Term of patent 14 years

Int. Cl. D11—02

U.S. Cl. D29—23 B

FIG. 1 is a plan view of a decorative ornament embodying my design.

FIG. 2 is a side elevation of the left-hand side of the decorative ornament shown in FIG. 1.

FIG. 3 is a side elevation of the right-hand side of the decorative ornament shown in FIG. 1.

FIG. 4 is a front elevation of the decorative ornament shown in FIGS. 1-3.

FIG. 5 is a rear elevation of the decorative ornament shown in FIGS. 1-3.

I claim:

The ornamental design of a decorative ornament, as shown.
